UNITED STATES PATENT OFFICE.

CHARLES M. DU MOND, OF CEDAR FALLS, IOWA.

GEARING FOR WASHING-MACHINES.

1,184,085.

Specification of Letters Patent. Patented May 23, 1916.

Application filed October 2, 1914. Serial No. 864,621.

To all whom it may concern:

Be it known that I, CHARLES M. DU MOND, a citizen of the United States of America, and a resident of Cedar Falls, Blackhawk 5 county, Iowa, have invented certain new and useful Improvements in Gearing for Washing-Machines, of which the following is a specification.

My invention relates to improvements in 10 washing machines, and the object of my improvement is to provide an improved and efficient mechanism for actuating the plunger-head contained in the tub of the machine. This object I have accomplished by 15 the mechanism which is hereinafter described and claimed, and which is illustrated in the accompanying drawing, in which:

Figure 1 is a side elevation of my improved washing machine, with a part of the 20 tub and cover broken or sectioned away, and with dotted lines showing the raised position of the cover and mechanism mounted thereon. Fig. 2 is a top plan view of said machine.

25 Similar numerals of reference denote corresponding parts throughout the several views.

The tub 17 has a cover 16 adapted to swing on the hinges 18, and a center bearing is 30 placed in an orifice in said cover to seat a vertical plunger-rod 1, the latter adapted to both reciprocate and rock within the bearing to impart like motions to the plunger-head 2 within the tub. The bearing forms 35 an integral part of a casting 14 fixedly mounted on said cover, and having an upright 15 whose upper end is bent laterally and orificed to seat the upper end of said plunger-rod. Said casting also has the 40 alined horizontal bearings 12 and 13 in which is rotatably seated a horizontal rotatable shaft 11. The inner end of said shaft 11 is provided with a crank 10 having a fixed crank-pin, the latter transversely ori- 45 ficed to seat rotatably a bifurcated pin 9, and one end of a cylindrical pin 6 is pivoted on a pintle 7 connecting the forks 8 of said pin 9. The vertical plunger-rod 1 has a transverse orifice in which the other end of 50 the pin 6 is both slidably and rotatably seated.

On the outer end of the shaft 11 is fixedly 55 mounted a gear-wheel 22 in mesh with another gear-wheel 23, the latter rotatably mounted on a stub-shaft 27 projected from said casting 14. A corner cap or casting 21

is fixedly mounted on said tub, and has a projecting stub-shaft 33 on which is rotatably mounted a fixedly connected pinion 24 and a fly-wheel 34. The numeral 32 denotes 60 a hand-lever which is pivoted at its lower end where incased in a socket-casting 31 on a stub-shaft 36 projected from said casting 21. A pitman 28 has one end pivoted to a pintle 35 on a lug 29 of the socket 31, while 65 its other end is curved downwardly and pivoted on a pin 27 projected from the gear-wheel 23. The cover 16 has a latch 19 adapted to be engaged by a catch 20 on the tub, to serve as separable fastening means. 70

It will be seen, by referring to Fig. 1, that the dotted lines indicate the raised position of the cover with the gear-wheels 22 and 23 mounted thereon, and that although the said cover swings up and down in the 75 usual way, that the said gears simply ride radially about the pinion 24 without becoming out of mesh with each other and without in any way interfering with the actions of the mechanism. This is due to the 80 fact that the pinion 24 and fly-wheel 34 are so mounted on the tub that their axis is alined with the hinged connection of the cover. The lever 32 when reciprocated, rotates said gears, with the shaft 11, the crank 85 10 and pins 9 and 6, causing the plunger-rod 1 to have a spiral motion, being a compounded motion of reciprocation and rotary movements, as the pin 6 both slides and rotates in in the orifice in said rod 1. The mechanism 90 shown therefore is always in working condition, whether the cover is raised or lowered.

Having described my invention, what I claim as new, and desire to secure by Letters Patent, is:

1. The combination with a relatively fixed support, a body hinged thereto, a coaxially connected fly-wheel and pinion rotatably mounted on the support in line with the 100 hinged joint of the body, a gear-wheel rotatably mounted on the body and in mesh with said pinion, a rotatable shaft mounted on said body, a gear-wheel fixed on said shaft and in mesh with said first-mentioned gear-wheel, a crank on said shaft, a bifurcated pin rotatably mounted in the crank-pin of said crank, a reciprocating alternating rotary-shaft mounted in said body, said shaft having a transverse orifice, and a pin mounted in said orifice for both sliding and rocking movements, one end of said pin 105 110

being pivoted between the forks of said bifurcated pin.

2. The combination with a relatively fixed support, a body hinged thereto, a shaft rotatably mounted on said body, a reciprocatory alternating rotary-shaft mounted in said body at an angle to the other shaft and spaced from one end thereof, the rotary-shaft having a crank provided with a fixed 5 transversely-orificed crank-pin, a bifurcated pin rotatably mounted in the transverse orifice of said crank-pin, said reciprocatory shaft having a transverse orifice, and a pin mounted slidably and rotatably in the trans- 10 verse orifice of said reciprocatory shaft, one end of the last-mentioned pin being mounted pivotally between the forks of said bifurcated pin.

3. In a washing machine, the combination with a relatively fixed support, and a body hinged thereto, of a fixedly coaxially connected fly-wheel and a relatively small pinion mounted rotatably on said support 15

with axis in line with the hinge connection of said body and support, a relatively 20 large gear-wheel rotatably mounted on said body and in mesh with said pinion, a second gear-wheel intermediate in dimensions between the pinion and the other gear-wheel and rotatably mounted on said support and 25 in mesh with the other gear-wheel, said gears adapted to swing radially about the pinion while remaining in mesh with each other, a plunger-shaft both oscillatory lengthwise and adapted to rock back and forth laterally, and operative elements connected between the second-mentioned gear-wheel and said plunger-shaft adapted to impart both said movements to said shaft when 30 said fly-wheel and gears are rotated.

Signed at Cedar Falls, Iowa, this 16th day of Sept., 1914.

CHARLES M. DU MOND.
